FOLDING TREADLE FOR SEWING MACHINES

Nathaniel E. Colegrove, Cleveland, Ohio, assignor
to White Sewing Machine Corporation, Cleve-
land, Ohio, a corporation of Delaware

Application February 6, 1940, Serial No. 317,579

14 Claims. (Cl. 312—30)

This invention relates to sewing machines and more particularly to sewing machines of the treadle operated type.

An object of the invention is to provide a treadle operated sewing machine and cabinet therefor, wherein the main driving wheel which drives the pulley of the sewing machine head is always concealed within a compartment formed in the cabinet, while the rockable treadle which actuates said wheel is operatively connected thereto in such manner that when not in use it can be swung from its horizontal operative position outside of said compartment into a substantially vertical concealed non-operative position within said compartment.

Another object is to provide a treadle operated sewing machine and cabinet therefor such as specified in the first named object and wherein the treadle may be swung from its operative position without the compartment to its inoperative substantially vertical concealed position within the compartment of the cabinet without disturbing the operative connection between it and the actuating mechanism for the driving wheel and independently of any movement of any of the parts of said mechanism and without requiring a complicated or unusual operative connection between the pitman of said mechanism and the part that actuates said pitman.

A further object of the invention is to provide a treadle operated sewing machine and cabinet therefor such as specified in the above named objects and wherein the actuating mechanism for the sewing machine is in the form of a unit assembly mounted within a compartment formed in the cabinet and to which unit assembly the treadle is pivotally connected, such that the pivotal movement of the treadle from its substantially vertical inoperative position within the compartment to its horizontal operative position outside of the compartment or vice versa does not affect the relationship of the operative parts of said actuating mechanism and is effected independently of any movement of any part of said mechanism.

A still further object of the invention is to provide a treadle operated sewing machine and cabinet therefor of the type previously referred to, and wherein the overall length of the treadle with its supports is considerably shortened when the treadle is in its substantially vertical or inoperative position within the compartment of the cabinet than when it is in its horizontal operative position without the compartment, whereby the requisite height of the compartment

and of the cabinet itself can be held to a minimum and in proper proportion to the width of the cabinet, thus providing a cabinet of pleasing appearance as well as one which supports the sewing machine head at the correct operative height.

Further and additional objects and advantages not hereinbefore specified will become apparent hereinafter during the detailed description which is to follow of an embodiment of the invention.

Referring to the accompanying drawings illustrating said embodiment of the invention,

Fig. 1 is a front elevational view of a sewing machine cabinet of the kneehole desk type, with certain portions of the cabinet broken away and shown in section in order to disclose the interior of the compartment and show in full lines the actuating mechanism unit assembly mounted therein, the treadle being shown in section, in the horizontal operative position extending across the knee or operating opening of the cabinet and by dash and dot lines when in the inoperative substantially vertical position within the compartment of the cabinet.

Fig. 2 is a horizontal sectional view taken substantially on line 2—2 of Fig. 1, looking in the direction of the arrows.

Fig. 3 is a vertical transverse section taken substantially on line 3—3 of Fig. 1, looking in the direction of the arrows, with the door of the compartment open and the treadle in the operative position.

Fig. 4 is a fragmentary detail sectional view on a larger scale than Fig. 2 and is taken on line 4—4 of Fig. 2, looking in the direction of the arrows.

Fig. 5 is a fragmentary detail sectional view on a larger scale than Fig. 2 and is taken substantially on line 5—5 of Fig. 2, looking in the direction of the arrows.

Fig. 6 is a fragmentary detail elevational view on a larger scale than Fig. 1 and is taken from the line 6—6 of Fig. 1, looking in the direction of the arrows, and

Fig. 7 is a fragmentary sectional and elevational view on a larger scale than Fig. 1 and shows the arrangement for supporting the free or left-hand end of the treadle shaft when the treadle is in its operative horizontal position in the kneehole or operating space of the cabinet.

The sewing machine cabinet illustrated herein is of the kneehole desk type and comprises a housing chamber 10 for the sewing machine

head. The upper or top side of the housing chamber 10 is provided with a work table 11 that has an opening therein in which the sewing machine head is pivotally mounted so that it can be dropped into an inoperative position in the housing chamber or can be swung upwardly therefrom into an operative position on the work table 11.

The opposite ends of the work table 11 have pivotally connected thereto swinging top leaves 12 and 13, which leaves when in the position shown in Fig. 1 cover the opening in the work table 11 and have their adjacent edges interfitting but when swung from said position to their open position form continuations of the work table 11. When the leaves 12 and 13 are in their open position the sewing machine head can be moved from its inoperative position within the housing chamber to its operative position on the work table 11. Inasmuch as the sewing machine head itself and the manner in which it is mounted on the cabinet for movement into and out of the housing chamber 10 form no part of the present invention and are well understood in the art, said sewing machine head and its mounting have not been illustrated herein.

The housing chamber 10 and work table 11 of the cabinet are supported by the four corner posts 14 and the posts at each end of the cabinet are interconnected by end panels 15 and 16. Connected to the front and rear posts 14 at the right-hand side of the cabinet, as viewed in the drawings, are front and rear panels 17 and 18, respectively, and these panels extend partway toward the left-hand side of the cabinet and form with the right-hand posts 14, end panel 16, the underside of the housing chamber 10, and a door later to be referred to, a compartment for housing and concealing the actuating mechanism for the sewing machine as well as the operating treadle when the latter is in its vertical inoperative position as will later be explained. The panels 17 and 18 are interconnected at their upper ends by the structure of the housing chamber 10, as can readily be understood and at their lower ends by means of a brace 19 extending from front to rear of the cabinet.

The compartment which has just been referred to is designated in the drawings by the letter A and said compartment can be closed and the parts located therein fully concealed by means of a door 20 hinged on its vertical rear edge to a vertically extending door strip 21 that is secured to the rear panel 18. It will be seen that the door 20 closes the open inner or kneehole side of the compartment when swung to closed position as indicated by the dot and dash lines in Fig. 2. When the door 20 is swung to its open position, as indicated in full lines in Figs. 1, 2 and 3, it extends part way across the kneehole or operating space of the cabinet and adjacent the rear of said space.

The door 20 is provided with a pull knob 22 to facilitate the opening of the same and is held in its closed position by means of a spring pressed ball or detent 23 mounted in its free vertical edge and which engages in a recess 24 formed on the inner side of the panel 17. The recess 24 is indicated in Fig. 2, although this sectional view actually is taken below said recess. The upper edge of the door adjacent its free edge is provided with a keeper recess 25 that is engaged by the retaining end of a spring pressed cabinet latch 26 mounted on the lower rear portion of the hous-

ing chamber 10 above the kneehole or operating space.

It will be understood that when the door 20 is moved to its open position its upper edge cams the cabinet latch 26 into position to allow the door to pass the same, after which the spring of the cabinet latch moves its retaining end into engagement with the keeper recess 25 in the door and the latter is held in its open position. Of course when it is desired to close the door it is necessary to manually move the cabinet latch 26 to allow the door to swing from its open position toward its closed position and when the door has passed the latch the latter can be released.

The actuating mechanism for the sewing machine head is in the form of a unit assembly and which assembly can be mounted as a unit in the compartment A. This unit assembly actuating mechanism comprises a supporting frame or bracket preferably in the form of an integral casting 27. This frame or bracket comprises a horizontally extending arm 27a from the middle of which there is a downwardly extending bowed or curved arm 27b. The arms 27a and 27b are also connected by a semi-circular guard 27c. The ends of the arm 27a outwardly of the guard 27c are secured to blocks mounted on the inner side of the end panel 16 within the compartment A, as indicated at 28. The arm 27b below the guard 27c is downwardly extended and is secured as indicated at 29 to a block similarly mounted on the inner side of the panel 16.

The casting 27 is similar to the ordinary combined frame or supporting bracket and dress guard customarily used on treadle operated sewing machines and is provided at its upper end and at the junction between the arms 27a and 27b with a bearing boss 30 in which is mounted a stub shaft 31. The supporting bracket 27 is spaced away from the panel 16 so that the main driving wheel 32 can be rotatably mounted on the stub shaft 31 between the supporting bracket 27 and the panel 16 and within the guard 27c.

The driving wheel 32 has its periphery grooved to receive the driving belt 33 that extends upwardly into the housing chamber 10 and passes around the driven pulley on the sewing machine head as will be well understood. The driving wheel 32 is provided on its side adjacent to the panel 16 with a boss 34 that rotatably carries a crank arm 35. The free end of this crank arm 35 is rigidly connected to the upper end of a pitman 36, the lower end of which pitman is provided with a bearing sleeve 37 that is freely and pivotally mounted on a connecting pin 38.

The connecting pin 38 also has freely and pivotally mounted on it the sleeve-like portion 39 formed at one end of the actuating arm 40. The opposite end of this actuating arm is provided with a yoke 41 and with an enlarged bearing sleeve portion 42 midway of the yoke.

The arm 27b of the supporting bracket 27 below its connection 29 to the panel 16 is provided with an integral downwardly and outwardly projecting extension 43, the lower end of which extension 43 is provided with an integral sleeve-like boss 44 which carries a fixed stub shaft 45. The bearing sleeve portion 42 of the arm 40 is rockably mounted on the stub shaft 45 by means of double cone ball bearings 46, as clearly indicated in Fig. 5.

It will be seen that the supporting frame or bracket 27, driving wheel 32, pitman 36 and actuating arm 40 can be operatively assembled into a unit and mounted in the compartment A of the

cabinet as a unit assembly and when the arm 40 and its bearing sleeve portion 42 are rocked on the stub shaft 45 the driving wheel 32 will be rotated through its operative connection with the pitman 36, which in turn is operatively connected to the free end of the arm 40.

It will also be noted that the actuating arm 40 is operatively connected to the pitman 36 by a simple pivotal connection, since said arm only rocks or oscillates and that the relationship between the arm 40 and the pitman 36 once the actuating mechanism has been mounted in the compartment as a unit assembly need not be changed.

Of course, in order that the operator can conveniently rock the arm 40 to effect rotation of the driving wheel 32 of the actuating mechanism, it is necessary to provide a treadle for such purpose and which treadle can be operatively located in the proper position in the kneehole or operating opening or space in the cabinet. It is also desirable that provision be made for moving this treadle when the sewing machine is not in use from its operative position in the kneehole opening or space of the cabinet to a concealed and inoperative position within the compartment A, and such movement should be accomplished independently of any movement of any part of the actuating mechanism.

In order to attain the ends just specified a treadle 47 is provided and this treadle preferably is in the form of a rectangular metal casting provided with a number of transverse openings. The treadle 47 on its right-hand end, as viewed in the drawings, and midway between its front and rear edges is provided with an integral downwardly facing channeled extension 48, the free end of which is forked or cut away to provide spaced lugs or ears 48a. The extension 48 is of such width that the lugs or ears 48a at the free end thereof extend between the sides of the yoke 41 of the arm 40.

The sides of the yoke 41 are provided with tapped openings therethrough into which are screwed pivot screws 49 having smooth conical inner ends 50 that project into conical openings 51 formed in the lugs or ears 48a of the extension 48 of the treadle. By this arrangement the right-hand end of the treadle, as viewed in the drawings, is operatively connected to the arm 40 and in such way that the treadle 47 can be swung from a horizontal operative position in the kneehole or operating space of the cabinet without the compartment A into a substantially vertical inoperative position within the compartment or vice versa. It will be well to note that the movement of the treadle from operative to inoperative position or vice versa does not affect in any way the unit assembly actuating mechanism or the operative relationships between the various parts of said mechanism and is effected independently of any movement of any part of said mechanism.

It will be appreciated that when the treadle 47 is in its horizontal operative position in the kneehole or operating opening or space of the cabinet means must be provided for supporting the free end of the treadle. The arrangement now to be described provides such means, and it will be noted it is of such character as not to increase materially the overall length of the treadle when the latter is in its substantially vertical inoperative position in the compartment A. Therefore, it is possible with this arrangement to have the cabinet and the compartment

A of minimum height, thus maintaining the dimensions of the cabinet in proper proportion and having the sewing machine head operatively located at the desired and proper height for convenient operation.

The treadle 47 on its under side is provided with longitudinally extending parallel ribs 52 equally spaced on each side of the longitudinal center line of the treadle. These ribs are interconnected at both ends and intermediate said ends by transversely extending ribs 52a. The left-hand and intermediate transverse ribs 52a are provided with openings axially aligned with each other and with the stub shaft 45. A shaft 53 slightly longer than the treadle is mounted in the openings of the lugs 52a so as to slide freely therein. The right-hand end of the shaft 53, as viewed in Fig. 1, has fixed therein a transversely extending pin 54 forming an abutment for one end of a coil spring 55 that surrounds the shaft and has its opposite end abutting the middle rib 52a. The opposite end of the shaft 53, i. e., the left-hand end as viewed in Fig. 1, is reduced and rotatably supports a roller 56 held in position by a washer 57 secured to the end of the shaft 53.

In moving the treadle 47 into its horizontal operative position within the kneehole opening of the cabinet the left-hand end of the shaft 53 is pulled outwardly against the tension of the spring 55 and the roller 56 passed downwardly through the enlarged opening 58 of a retaining bracket 59 that is secured to the inner side of the panel 15 of the cabinet. Then when the operator releases his hold on the shaft 53 the spring 55 moves said shaft toward the right, as viewed in the drawings, to bring the roller 56 beneath the ears 60 formed on the upper side of the retaining bracket 59 and into engagement with the inner side of the outer end of said bracket.

It will now be seen that the treadle 47 is supported at its opposite ends for oscillating or rocking movement when in the horizontal operative position. When the treadle is rocked or oscillated the weight or pressure of the treadle on the shaft 53 will, due to friction, cause said shaft to rock or oscillate with the treadle and the free end of said rocking or oscillating shaft will move in the roller 56. By using the roller 56 and the retaining bracket 59 the diameter of the bearing for the shaft 53 is reduced and also the bearing between the shaft and the roller can be lubricated, thus avoiding the necessity of putting lubricant in the retaining bracket 59.

In moving the treadle 47 from its horizontal operative position into its vertical inoperative position the operator grasps the shaft 53, moves the same toward the left against the tension of the spring 55 and until the roller 56 has passed from beneath the ears 60 and lies in line with the large opening 58 of the bracket 59, whereupon the shaft 53 with the treadle can be swung vertically upwardly about the pivot screws 49 and into the compartment A.

When the treadle 47 is sufficiently vertically inclined the shaft 53 will slide downwardly by gravity until the right-hand end of the shaft, as viewed in Fig. 1, engages the right-hand rib 52a of the treadle, as which time only a relatively short portion of the shaft 53 at the end carrying the roller 56 will extend beyond the free end of the treadle. This results in materially shortening the overall length of the treadle including the shaft and allows it to be accommo-

dated in the compartment A which, as has been previously pointed out, can be of minimum height as can also the cabinet.

As the treadle and shaft 53 are swung into the compartment A the exposed or roller carrying end of the shaft 53 strikes a bail 61 that is pivotally connected to brackets 62 secured to a structural element 63 extending from front to rear of the cabinet above the doorway to the compartment A. The exposed end of the shaft 53 swings the bail 61 inwardly and allows the end of said shaft to pass thereby, after which the bail will swing downwardly by gravity until it engages the structural element 63, in which position it acts to retain the shaft 53 and the treadle 47 in the substantially vertical concealed inoperative position within the compartment A.

Assuming that the treadle 47 is in the inoperative position within the compartment A, as indicated in dot and dash lines in Fig. 1, and the door 28 of said compartment is in the closed position, the operator desiring to use the sewing machine moves the door 28 to its open position and until it is engaged by the cabinet latch 26 and then pushes the treadle and shaft 53 further inwardly of the compartment A and manually raises the bail 61 upwardly to a position wherein it clears said shaft, after which the treadle and shaft can be swung downwardly and outwardly about the pivot screws 48 and into a substantially horizontal position in the knee opening. This is followed by engaging the roller 56 in the retaining bracket 59, as previously described, after which, so far as the treadle and the actuating mechanism are concerned, the machine is ready for operation.

It will be well to again note that the movement of the treadle 47 from inoperative to operative position and vice versa does not affect the relationship of the various parts of the unit assembly actuating mechanism, since the pivotal movement of the treadle is solely about the pivot screws 49 and is independent of any movement of any part of said mechanism.

Although a preferred embodiment of the invention has been illustrated and described herein it will be understood that the invention is susceptible of various modifications and adaptations within the scope of the appended claims.

Having thus described my invention, I claim:

1. In a sewing machine, a cabinet having a chamber for the head, an operating opening or space beneath said chamber, and a compartment adjacent said space or opening and at one end of said cabinet; an actuating mechanism for said head mounted in said compartment, a treadle, means forming a combined operative and supporting pivotal connection between said mechanism and one end of said treadle and always entirely within said compartment and about which connection the treadle may swing, independently of any movement of any part of said mechanism, from a substantially vertical inoperative position within said compartment to a horizontal operative position in said space or opening and without said compartment, and means for rockably supporting the free or other end of said treadle when in said operative position.

2. In a sewing machine, a cabinet having a chamber for the head, an operating space or opening beneath said chamber, and a compartment adjacent said space and at one end of said cabinet; an actuating mechanism for said head mounted in said compartment, a treadle, means

forming a combined operative and supporting pivotal connection between said mechanism and one end of said treadle and always entirely within said compartment and about which connection the treadle may swing, independently of any movement of any part of said mechanism, from a substantially vertical inoperative position within said compartment to a horizontal operative position in said space or opening and without said compartment, and means for rockably supporting the free or other end of said treadle when in said operative position, said last mentioned means including a shaft slidably carried by said treadle and substantially contained within the length of the treadle when the latter is in its inoperative position within the compartment.

3. In a sewing machine, a cabinet having a chamber for the head, an operating opening or space beneath said chamber, and a compartment adjacent said space and at one end of said cabinet; an actuating mechanism for said head mounted in said compartment, a treadle, means forming a combined operative and supporting pivotal connection between said mechanism and one end of said treadle and always entirely within said compartment and about which connection the treadle may swing, independently of any movement of any part of said mechanism, from a substantially vertical inoperative position within said compartment to a horizontal operative position in said space and without said compartment, and means for rockably supporting the free or other end of said treadle when in said operative position, said last means including a shaft slidably carried by said treadle and substantially contained within the length of the treadle when the latter is in its inoperative position within the compartment, and a spring on said shaft tending to urge the same toward said one end of said treadle.

4. In a sewing machine, a cabinet having a chamber for the head, an operating space or opening beneath said chamber, and a compartment adjacent said space or opening and at one end of said cabinet; an actuating mechanism for said head mounted in said compartment, a treadle, means forming a combined operative and supporting pivotal connection between said actuating mechanism and one end of said treadle and about which the treadle may swing, independently of any movement of any part of said mechanism, from a substantially vertical inoperative position within said compartment to a horizontal operative position in said space and without said compartment, and means for rockably supporting the free or other end of said treadle when in said operative position, said means including a bracket carried by the other end of said cabinet and within said space or opening, a shaft extensibly carried by said treadle, a roller mounted on one end of said shaft and cooperating with said bracket, and a spring carried by said shaft and acting to maintain said roller in engagement with said bracket.

5. In a sewing machine, a cabinet having a chamber for the head, an operating space beneath said chamber, and a compartment adjacent said space and at one end of said cabinet; an actuating mechanism for said head in the form of a unit assembly mounted and always contained entirely in said compartment and including an actuating arm and a pivotal bearing for said arm about which said arm can rock; a treadle, means pivotally connecting one end of

said treadle to said arm to support said one end of the treadle to rock with said arm and to swing, independently of any movement of said arm, from a substantially vertical inoperative position within said compartment to a horizontal operative position in said space and without said compartment, and means for rockably supporting the free or other end of said treadle when in said operative position.

6. In a sewing machine, a cabinet having a chamber for the head, an operating space beneath said chamber, and a compartment adjacent said space and at one end of said cabinet; an actuating mechanism for said head in the form of a unit assembly mounted and always contained entirely in said compartment, said mechanism being of the type including a driving wheel, a pitman connected thereto, an actuating arm connected to said pitman, and a pivotal bearing for said arm and about which it can rock; a treadle, means pivotally connecting one end of said treadle to said actuating arm to support said one end of the treadle to rock with said arm and to be swung, independently of any movement of said arm, from a substantially vertical inoperative position within said compartment to a horizontal operative position in said space and without said compartment, and means for rockably supporting the free or other end of said treadle when in said operative position.

7. In a sewing machine, a cabinet having a chamber for the head, an operating space beneath said chamber and a compartment adjacent said space and at one end of said cabinet, an actuating mechanism for said head and in the form of a unit assembly mounted and always contained entirely in said compartment, said mechanism being of the type including a supporting bracket, a driving wheel rotatably carried by said bracket, a pitman operatively connected to said wheel, a bearing support carried by said bracket, an actuating arm rockably mounted on said bearing support and operatively connected to said pitman; a treadle, means pivotally connecting one end of said treadle with said arm to support said one end of the treadle to rock with said arm and to be swung, relative thereto and independently of any movement thereof, from a substantially vertical inoperative position within said compartment to an operative position in said space and without said compartment, and means for rockably supporting the free or other end of said treadle when in said operative position.

8. In a sewing machine, a cabinet having a chamber for the head, an operating space beneath said chamber and a compartment adjacent said space and at one end of said cabinet; an actuating mechanism for said head always located entirely within said compartment and in the form of a unit assembly including a supporting bracket attached to said one end of said cabinet and within said compartment; a rockable treadle for operating said actuating mechanism, means entirely within said compartment operatively associating said treadle and mechanism and pivotally connecting one end of said treadle with said bracket to support said one end and enable said treadle to be swung, independently of any movement of said actuating mechanism, from a substantially vertical inoperative position within said compartment to an operative substantially horizontal position in said space and without said compartment.

9. In a sewing machine of the type including a cabinet having a chamber for the head, an op-

erating space beneath said chamber, a compartment adjacent said space and at one end of said cabinet, and an actuating mechanism for said head and located in said compartment; a rockable treadle for operating said mechanism, and means carried by said one end of said cabinet and always entirely within said compartment and forming the sole operative connection between said treadle and mechanism and pivotally supporting one end of said treadle for movement about a substantially horizontal axis whereby said treadle may be swung from a substantially vertical inoperative position within said compartment to a substantially horizontal operative position without said compartment.

10. In a sewing machine of the type including a cabinet having a chamber for the head, an operating space beneath said chamber, a compartment adjacent said space and at one end of said cabinet, and an actuating mechanism for said head and located in said compartment; a rockable treadle for operating said mechanism, and means carried by said one end of said cabinet and always entirely within said compartment and forming the sole operative connection between said treadle and mechanism and pivotally supporting one end of said treadle for movement about a substantially horizontal axis whereby said treadle may be swung from a substantially vertical inoperative position within said compartment to a substantially horizontal operative position without said compartment, and means for supporting the other end of said treadle relative to the other end of said cabinet when said treadle is in the operative position.

11. In a sewing machine of the type including a cabinet having a chamber for the head, an operating space beneath said chamber, a compartment adjacent said space and at one end of said cabinet, and an actuating mechanism for said head and located in said compartment; a rockable treadle for operating said mechanism, and means carried by said one end of said cabinet and always entirely within said compartment and forming the sole operative connection between said treadle and mechanism and pivotally supporting one end of said treadle for movement about a substantially horizontal axis whereby said treadle may be swung from a substantially vertical inoperative position within said compartment to a substantially horizontal operative position without said compartment, and means for supporting the other end of said treadle relative to the other end of said cabinet when said treadle is in the operative position, said last means including a shaft slidably carried by said treadle.

12. In a sewing machine of the type including a cabinet having a chamber for the head, an operating space beneath said chamber, a compartment adjacent said space and at one end of said cabinet, and an actuating mechanism for said head and located in said compartment; a rockable treadle for operating said mechanism, and cooperating means carried by said mechanism and treadle and pivotally supporting one end of said treadle to provide for swinging movement of said treadle from a substantially vertical position within said compartment to a substantially horizontal position without said compartment, said means also operatively connecting said mechanism and treadle whereby rocking of said treadle operates said mechanism.

13. In a sewing machine of the type including a cabinet having a chamber for the head, an op-

erating space beneath said chamber, a compartment adjacent said space and at one end of said cabinet, and an actuating mechanism for said head and located in said compartment and supported by said one end of said cabinet; a rockable treadle for operating said mechanism and cooperating means carried by said mechanism and treadle and forming the sole support for said treadle within said compartment, said means pivotally connecting said treadle with said mechanism along a substantially horizontal axis whereby said treadle may be swung from a substantially vertical inoperative position within said compartment to a substantially horizontal operative position without said compartment, said means also operatively connecting said treadle and mechanism whereby rocking movement of said treadle operates said mechanism.

14. In a sewing machine, a cabinet having a

chamber for the head, an operating space beneath said chamber, and a compartment adjacent said space and at one end of said cabinet; an actuating mechanism for said head mounted in said compartment and including an actuating arm having a forked portion and a pivotal support for said arm; a rockable treadle for operating said mechanism and having a forked portion cooperating with the forked portion of said actuating arm, and means pivotally connecting the forked portion of said arm and the forked portion of said treadle whereby rocking movement of said treadle operates said actuating mechanism and said treadle can be swung from an inoperative substantially vertical position within said compartment to an operative substantially horizontal position without said compartment.

NATHANIEL E. COLEGROVE.
